(57) CLAIM

The ornamental design for a display packet, as shown and described.

DESCRIPTION

FIG. 1 is a front and side perspective view of a display packet showing my new design;

FIG. 2 is a rear and side perspective view of the display packet;

FIG. 3 is a front view of the display packet;

FIG. 4 is a top edge view of the display packet as shown in FIG. 3;

FIG. 5 is a bottom edge view of the display packet as shown in FIG. 3;

FIG. 6 is a rear view of the display packet;

FIG. 7 is a left edge view of the display packet as shown in FIG. 6; and,

FIG. 8 is a right edge view of the display packet as shown in FIG. 6.

The broken lines shown in the figures are for illustrative purposes only and form no part of the claimed design.
